UNITED STATES PATENT OFFICE.

WILLIAM R. WOOD, OF LEWISTOWN, PENNSYLVANIA, ASSIGNOR OF ONE-HALF TO THOMAS S. JOHNSON, OF SAME PLACE.

AX-FORGING DIE.

SPECIFICATION forming part of Letters Patent No. 653,602, dated July 10, 1900.

Application filed October 16, 1899. Serial No. 733,805. (No model.)

To all whom it may concern:

Be it known that I, WILLIAM R. WOOD, a citizen of the United States, and a resident of Lewistown, Mifflin county, Pennsylvania, 5 have invented certain Improvements in Ax-Forging Dies, of which the following is a specification.

The object of my invention is to so construct a die for forging axes as to provide for readily changing the shape of the head or poll of the ax or compensating for excess or deficiency of metal in the head portion of the blank; and these objects I attain in the manner hereinafter set forth, reference being had 15 to the accompanying drawings, in which—

Figure 1 is a sectional view of the upper and lower dies of an ax-forging press, the lower die being constructed in accordance with my invention and the dies being closed 20 or in the position which they assume when acting upon the blank. Fig. 2 is a plan or top view of the lower die. Fig. 3 is a perspective view, on a larger scale, of the head-block used in connection with said die. Fig. 4 is 25 an end view of said block, and Figs. 5 and 6 are views of different forms of head-blocks which may be substituted for that shown in Fig. 2.

My invention relates to that class of ax-forging dies known as "open" dies—that is to say, dies in which the matrices for the reception of the ax-blank extend out to the edges of the dies at the head end—such dies being much more readily made than closed 35 dies, because the head portions of the matrices can be formed by planing or milling instead of by chipping and filing, as is necessary in the case of such closed dies. When such open dies are used, however, a third element or head-block must be employed for filling the open ends of the matrices and properly confining and shaping the metal of the head or poll of the ax, and usually this head-block is a piece independent of the dies and 40 carried by a structure beyond the side of the press, a plan which is not only expensive, but also cumbersome and inconvenient.

In carrying out my invention I use a head-block which is carried by and forms in effect 45 part of the lower die of the press, and I mount said head-block upon said lower die so that

it can be readily adjusted thereupon or removed from and replaced thereon, thus providing a means of compensating for excess in or deficiency of metal in the blanks and also 55 permitting a ready change of head-block when a change in the shape of the head or poll of the ax is required.

In the drawings, 1 represents the upper die, which is an open die of the usual character, 60 my invention having no reference thereto. The lower die 2, however, has a longitudinal extension 3, in which is a transverse recess 4, preferably dovetailed and adapted for the reception of a dovetailed rib 5 upon the under 65 side of the head-block 6 and also for receiving wedges 7 and 8, which are interposed between said rib and the walls of the recess 4.

The head-block 6 fits snugly into the head portions of the matrices 9 when the two dies 70 are brought together, and the inner face of the head-block is shaped so as to conform to the desired configuration of the head or poll of the ax, three different shapes of such head block being shown in the drawings. 75

It occasionally happens that a run of blanks will exceed slightly the normal weight, in which case the excess of metal must be forced into the head portion of the ax, and by proper adjustment of the wedges 7 8 the head-block 80 6 can be backed off sufficiently to accommodate such excess of metal. On the other hand, the blanks sometimes waste away in the heating process, so that they fail to come up to weight and do not properly fill out in the 85 heads. To compensate for this, the head-block may be moved inward slightly, as will be readily understood.

By removing the wedges the rib 5 of the head-block can be withdrawn from the recess 90 4 and another head-block inserted in place of the one removed and then secured in the desired position by reinsertion of the wedges.

The dies have in addition to the matrices 9 for the formation of the ax the usual recesses 95 10 for the reception of the mandrel 11, which passes through the eye of the ax and remains therein during the forging or pressing operation.

Having thus described my invention, I 100 claim and desire to secure by Letters Patent—

1. An ax-forging die-block having an open-ended matrix and a head-block closing said open end of the matrix and carried wholly by, but adjustable upon the die-block, so as to project more or less into said open end of the matrix, substantially as specified.
2. An ax-forging die-block having an open-ended matrix, and a head-block closing said open end of the matrix, and carried wholly by, but detachable from the die-block, substantially as specified.
3. An ax-forging die-block having an open-ended matrix, and a transverse recess, a head-block closing said open end of the matrix and having a rib contained in said transverse recess and means whereby said rib is secured in the recess, substantially as specified.
4. An ax-forging die-block having an open-ended matrix, a head-block closing said open end of the matrix and carried wholly by the die-block, said head-block being movable so as to project more or less into said open end of the matrix, and adjusting devices for said head-block also carried wholly by the die-block, substantially as specified.

In testimony whereof I have signed my name to this specification in the presence of subscribing witnesses.

WILLIAM R. WOOD.
